CLAIM

The ornamental design for a tool box, as shown and described.

DESCRIPTION

FIG. 1 is a top-front-left perspective view of a tool box showing our new design according to a first embodiment; FIG. 2 is a bottom-rear-right perspective view thereof; FIG. 3 is a front elevational view thereof; FIG. 4 is a rear elevational view thereof; FIG. 5 is a left-side elevational view thereof; FIG. 6 is a right-side elevational view thereof; FIG. 7 is a top plan view thereof; FIG. 8 is a bottom plan view thereof; FIG. 9 is a magnified view of the portion shown and designated in FIG. 1; FIG. 10 is a top plan view of the tool box showing our new design according to a second embodiment, the second embodiment being identical to the first embodiment; and, FIG. 11 is a front elevation view thereof. The broken lines in FIGS. 1-11 are for the purpose of illustrating portions of the tool box that form no part of the claimed design. The tool box is shown with a symbolic break in its length in FIGS. 10-11. The appearance of any portion of the article between the break lines forms no part of the claimed design.
